UNITED STATES PATENT OFFICE.

ROY R. WILEY, OF BUFFALO, NEW YORK, ASSIGNOR TO FLEXLUME CORPORATION, OF BUFFALO, NEW YORK, A CORPORATION OF NEW YORK.

ILLUMINATED SIGN.

Application filed January 27, 1922. Serial No. 532,238.

To all whom it may concern:

Be it known that I, ROY R. WILEY, a citizen of the United States, residing at Buffalo, in the county of Erie and State of New York, have invented certain new and useful Improvements in Illuminated Signs, of which the following is a specification.

This invention relates to improvements in illuminated signs, proposing a sign which is especially adapted for indoor use as in banks, hotels, office buildings and show windows. For such use there is required a small compact sign structure having small letters or characters, that is to say letters or characters ordinarily of not greater than two or three inches in height and also having provision for the effective display and illumination of such letters or characters whereby they may be easily read at a considerable distance from the sign.

The principal object of the invention is to provide a sign which, meeting the requirements stated, will enhance in material degree the effective display and illumination of the letters or characters, more particularly by an arrangement thereof favorable to legibility when the sign is viewed from a distance or at an angle, and by combining in the illumination of the letters or characters the qualities of brilliance, warmth and uniformity.

A further object is to provide a sign for the use stated which shall be attractive in appearance, economically maintained, simple in structure and wherein the enclosed parts are readily accessible for renewal or other purposes.

With the above objects in view the invention consists generally in certain novel features of structure and combination as hereinafter claimed and which will be set forth in detail as the description proceeds.

Embodiments of the invention in connection with both single face and double face signs are illustrated in the accompanying drawings, wherein:

Figure 1 is a front view of a single face sign.

Figure 2 is a cross sectional view of a single face sign.

Figure 3 is a vertical sectional view on the line 3-3 of Figure 2.

Figure 4 is a horizontal view on the line 4-4 of Figure 2.

Figure 5 is a cross sectional view of a double face sign.

Referring to Figures 1 to 4 inclusive which show a sign of the single face type:

The sign structure includes a box 1 which encloses the principal operating parts and may be of any required dimensions and outline, a rectangular box being shown. The front wall 2 of the box includes a panel 3 of clear transparent glass through which the sign letters or characters are exposed to view and a frame 4 for the support of said panel, the latter being secured in any suitable manner, for example by clips 5 which hold the panel against the inner face of the frame. In order to give ready access to the interior of the box the front wall 2 may be movably mounted in any suitable manner, for example by hinges 6 connecting the top wall of the box and the upper bar of the frame 4.

The sign includes letters or characters which are incorporated in a sign board and are preferably displayed against a suitably contrasting background. In certain aspects of the invention the letters or characters may be produced in any desired way. As preferred and according to certain features of the invention the sign board is arranged within the box 1 at an acute angle to the vertical axis of the panel 3 whereby said board in a direction between its upper and lower edges converges toward said panel. The sign is otherwise constructed whereby the sign board constitutes the rear wall of an illuminating chamber 7 whereof the front wall is constituted by the panel 3. Owing to the inclined arrangement of the sign board the chamber 7 progressively diminishes in depth in a direction normal to the plane of the sign board and consequently said chamber will be of substantially greater area at one vertical extreme than at the other.

The sign includes a chamber 8 arranged behind the chamber 7. According to the invention rays of light from the chamber 8 are directly emitted into the chamber 7, entering through the vertical extreme thereof of larger area. The electric lamps which are the sources of light are preferably arranged in the chamber 8, these lamps, as 9, being provided in any desired number and of any desired power. The lamps 9 in any case are hidden from view from a position

in front of the sign and they are preferably arranged immediately adjacent the larger vertical extreme of the chamber 7.

Different circumstances of use will variously require the signs to be arranged for view from above or from below. For example a sign for a bank teller's wicket will usually have an overhead arrangement and will be viewed from below and signs for use in show windows may sometimes be arranged on the floor of the window for view from above. The particular inclination of the sign board will depend on whether the sign is to be viewed from above or below. The drawings assume a sign for overhead arrangement and for view from below in which case, as shown, the sign board converges upwardly toward the panel 3, the chamber 7 is of greatest area at its lower vertical extreme and the lamps 9 are arranged adjacent the bottom of the box 1. If the sign is to be positioned for view from above the arrangement just described is reversed, that is to say, the sign board will converge downwardly toward the panel 3, the chamber 7 will be of greatest area at its upper vertical extreme, and the lamps 9 will be arranged adjacent the top of the box 1, and for the purpose of illustrating such a sign a mere inversion of Figure 2 will be sufficient.

While, as above stated, in certain aspects of the invention, that is to say in certain novel combinations of elements into which the invention may be resolved, the sign letters or characters may be produced in any desired way, in certain other aspects of the invention, involving other novel combinations of elements, it is requisite that the sign letters or characters be produced in connection with a translucent display, the sign board in such a case, and, according to the invention, being arranged to receive light rays on both faces, that is to say from within both chambers 8 and 7. As preferred the letters or characters are translucent and stand out against an opaque background although the arrangement can, of course, be reversed, that is to say the letters or characters can be opaque and stand out against a translucent background; or if desired the letters and background can both be translucent. Thus the visible faces of the sign board, that is to say of the sign letters or characters in the embodiment shown and preferred, are illuminated by the light rays impinging thereon from within the chamber 7 while at the same time the sign letters or characters transmit and diffuse the light from the chamber 8. In other words the translucent letters or characters are illuminated externally and also from within the chamber 8 with the result that their illumination most effectively combines the qualities of warmth and extreme brilliance. In practice it has been found that the best results are obtained by

using raised or relief letters or characters which are pressed from sheets of milk white translucent glass, letters of such description being set forth in Letters Patent No. 1,224,253 of May 1, 1917. Such letters are herein shown at 10 and, as regards the present invention, may all (as comprising the full text of the sign) be pressed from a single plate of glass 11; such practice is, however, suggested merely as one which will be convenient in many cases.

The sign board, in the present instance the plate 11 provided with the letters 10, is carried by a bracket 12 in which the upper and lower walls of the chamber 7 are incorporated. The sign board is arranged at the rear of said chamber and constitutes in effect the rear wall thereof, physical portions of said rear wall being incorporated in the bracket 12. The chamber 7 is completed by end walls 13 which are arranged at the ends of the bracket 12 and extend between said bracket and the frame 4. The sign board may be secured to the bracket in any suitable manner. In the present embodiment this is effected by securing strips 14 suitably united to the bracket 12 and overlying the upper and lower edge portions of the plate 11 to hold said plate against the rear wall part of the bracket. Where, as in the construction shown and preferred, the sign letters are translucent and illuminated both from the front and rear, the rear wall portion of the bracket 12 is provided with an opening 30 through which light rays may pass from the chamber 8. The bracket 12 may be secured in operative position in any desired manner and to any desired part of the sign structure. It is preferably secured so that it may be conveniently dissociated from the box 1 and from the movable front wall 2. These purposes are served, for example, and as shown, by securing the bracket 12 to the frame 4 by means of screws 15 which engage upper and lower extension strips 16 projecting from the upper and lower walls of the bracket. By such arrangement when the front wall 2 is swung open it carries with it the bracket 12, thereby giving complete and open access to the chamber 8. If it be desired to remove the bracket 12 all that is necessary is the removal of the screws 15 and thereupon complete access may be had to the chamber 7. The wall 2 may be held closed in any suitable manner, for example by a screw 17 fitted in the bottom of the box 1 and engaging a finger 18 projecting from the lower extension strip 16. By withdrawing the screw 17 the wall 2 is released and may be swung open as will be obvious.

The vertically extreme wall of the chamber 7 of greatest area, that is to say the lower wall in the embodiment disclosed, is provided with a longitudinal slot 19 co-extensive with the lettered portion of the sign

board or is otherwise of suitable open formation whereby light from the chamber 8 may pass into the chamber 7 to illuminate the visible face of the sign board. The best results are secured by the arrangement shown according to which the lamps 9 are located behind the wall in which the slot 19 is provided, and a reflector 20 is located behind the lamps, such reflector preferably consisting of one or more plates of translucent milk white glass of the same character as that used for the letters 10 and being secured against the bottom or top of the box 1, as the case may be, by suitable clips 21. The direct rays of light admitted by the slot 19 impinge upon the visible face of the sign board, and also upon the glass panel 3 which acts as a reflector and thereby the visible face of the sign board is illuminated, both directly and reflectively with resultant material advantage in the substantial uniformity of the illumination of the sign board. This is for the reason that although the illuminating effect of the rays directly impinging upon the sign board diminishes toward the ends or portions of the letters remote from the slot 19, such diminution is compensated by the rays which are reflected toward said remote ends or portions by the glass panel 3. Having reference to the embodiment shown and in order to prevent the portions of the letters nearest the slot 19 from being too brilliantly illuminated as compared with the remaining portions of the letters, in other words in order to prevent the substantial uniformity of the illumination from being impaired, a longitudinal strip 22 forming an opaque barrier is so arranged between the chamber 8 and the sign board as to intercept the rays of light which would otherwise directly strike upon the ends of the letters nearest the slot 19. This strip 22 is conveniently provided as a part of the wall in which the slot 19 is formed and is located between said slot and the sign board.

The reflecting quality of the panel 3 is best utilized for the purpose in view by arranging the wall in which the slot 19 is formed at a suitable forward inclination. As thus arranged said wall is preferably provided with a flange 23 along the forward edge of the slot 19 and which projects into the chamber 7. The flange 23 is approximately equal in vertical extent to the distance in the vertical direction between the front and rear edges of the slot 19 and its office is two-fold, namely to insure the complete concealment of the lamps in those cases where the sign may be arranged approximately at the level of the eyes and to locate the angles of reflection of the light rays directly striking on the panel 3 favorably to the uniformity of the illumination of the sign board.

Where, as shown and preferred, the sign board includes translucent letters 10 the lamps 9 are arranged above or below the letters (according to the elevation at which the sign may be supported) so as to avoid any possibility of glare spots while at the same time to emit most of the light rays into the chamber 8. The effective illumination of the faces of the letters exposed in the chamber 8 is aided by utilizing the rear wall of the sign box as a reflector, said wall having a reflecting finish or otherwise being made reflective and by providing a suitable reflector 24 along the wall opposite to that which carries the reflector 20. The chamber 8 is preferably continuous and the lamps 9 are arranged therein at substantially regular intervals whereby the light from each lamp illuminates all of the letters. Except for the letters 11 the plate 10 is rendered opaque and of a color which suitably contrasts with the color of said letters. For this purpose an opaque, preferably black, coating 25 is applied to the face of the plate 10 which is exposed in the chamber 7. All other parts exposed to view in the chamber 7 are preferably given a similar finish whereby the illuminated white letters stand out against a continuous background of a single contrasting color and the structural securing strips 14, flange 23 and other structural details have no individual definition in appearance but rather appear as continuous parts of a uniform background so that their presence will not be apparent or noticed. The uniformity and continuity of such background is indicated in Figure 1 from which details of the strip 14 and flange 23 have been advisedly omitted in order that the actual appearance of the sign may be closely simulated.

The box 1 is formed with suitable openings 26 in the walls of the chamber 8 for the purposes of ventilation and is preferably provided within said chamber with a suitable conduit 27 for the feed wires of the lamps 9. These may be of any standard form, their bases being fitted in sleeves or sockets 28 which are carried by suitable supporting brackets 29.

Referring to Figure 5:

The sign shown in this figure is of the double face type and embodies the same essential features of structure and operation as the single face sign described. This double face sign includes side walls 2^a which are structurally and functionally similar to the front wall 2 of the single face sign and are accordingly provided with clear glass panels 3^a. In the double face sign there are two illuminating chambers, that is to say each wall 2^a is provided in association with a corresponding illuminating chamber 7^a similar in all respects to the chamber 7 above described. A chamber 8^a,

corresponding to the chamber 8 previously described, and the lamps 9^a enclosed therein are common to the two chambers 7^a. Suitable reflectors 20^a are arranged behind the 5 lamps 9^a and other suitable reflectors 24^a are arranged opposite the reflectors 20^a. The benefits of cross reflection, as explained in said Letters Patent No. 1,224,253, are obtained by the letter carrying plates 11^a, each 10 of which reflects light to the other.

It will be understood that the word "letters" as used in certain of the following claims is adopted, as a measure of convenience, as a generic term applicable to letters, strictly so called, characters, or other display matter.

Having fully described my invention, I claim:

1. In an illuminated sign, in combination, 20 a sign box having a wall provided with a clear glass panel, a sign board visible through and inclined at an acute angle to said panel, an illuminating chamber of which said board forms the rear wall and said panel the front wall and which is otherwise provided with upper, lower and end walls, the upper and lower walls being of different area owing to the inclination of said board and the wall of greater area being inclined between said board and said panel and having an opening, an opaque barrier between said opening and said panel and a flange in front of said opening and projecting into said chamber, said flange 25 being of sufficient depth to conceal said opening from view, and a source from which light is admitted through said opening into said chamber.

2. In an illuminated sign, in combination, 40 a sign box having a movably mounted wall provided with a clear glass panel, a sign board visible through said panel, an illuminating chamber of which said board forms the rear wall and said panel the front wall, and a bracket carrying said board and in which the other walls of said chamber are incorporated, said bracket having an opening and being removable with respect to said box and said movably mounted wall, 45 and lamps arranged in the box beyond said chamber and from which light is admitted into said chamber through said opening.

3. In an illuminated sign, in combination, 55 a sign box having a wall provided with a clear glass panel, a sign board visible through said panel and provided with translucent letters, and lamps in said box arranged to illuminate both the front and rear faces of said sign board.

4. In an illuminated sign, in combination, 60 a sign box having a wall provided with a clear glass panel, a sign board visible through said panel and having translucent quality in certain portions and opaque quality in other portions and letters incor-

porated in the portions having one of said qualities, and lamps in said box arranged to illuminate both the front and rear faces of said board.

5. In an illuminated sign, in combination, a 70 sign box having a wall provided with a clear glass panel, a sign board visible through and inclined relatively to said panel, said board being provided with portions of translucent quality and other portions of opaque 75 quality and with translucent letters incorporated in the portions having one of said qualities, and lamps in said box arranged to illuminate both the front and the rear faces of said board, the panel serving as a reflector and the board having its front face illuminated by the combination of the direct rays from said lamps and the rays reflected by said panel.

6. In an illuminated sign, in combination, 80 a sign box having a wall provided with a clear glass panel, a sign board visible through said panel and provided with portions of translucent quality and other portions of opaque quality and with translucent 85 letters incorporated in the portions having one of said qualities, an illuminating chamber of which said panel forms a wall and which is provided with an opening for light, said box having a second chamber in which said illuminating chamber is enclosed, and lamps in said second chamber to supply light to the same and also to supply light through said opening to said illuminating chamber, said board being illuminated by the light 90 from both chambers.

7. In an illuminated sign, in combination, 95 a sign box having a wall provided with a clear glass panel, which serves as a reflector, a sign board visible through and inclined 100 relatively to said panel and provided with portions of translucent quality and other portions of opaque quality and with translucent letters incorporated in the portions 105 having one of said qualities, an illuminating chamber of which said panel forms a wall and which is provided with an opening for light, said box having a second chamber in which said illuminating chamber is enclosed, and lamps in said second chamber to supply 110 light to the same and also to supply light through said opening to said illuminating chamber, said board being illuminated by the light from both chambers and, in the 115 illuminating chamber, being illuminated by the direct light and by the light reflected by said panel.

8. In an illuminated sign, in combination, 120 a sign box having opposed walls, each provided with a clear glass panel, an illuminating chamber associated with each panel and having an opening, a sign board for each illuminating chamber and forming a wall thereof, each sign board being visible 125 through the corresponding panel and pro- 130

vided with portions of translucent quality and other portions of opaque quality and with translucent letters incorporated in the portions having one of said qualities, the 5 box having a chamber between said illuminating chambers, said letters having their faces exposed in the illuminating chambers and in the intermediate chamber and lamps

in said last named chamber by which the inner faces of the boards are illuminated, 10 said lamps being arranged whereby light therefrom may pass through said openings into the illuminating chambers to illuminate the outer faces of the boards.

In testimony whereof I affix my signature.
ROY R. WILEY.
